US0D1081886S

(12) **United States Design Patent** (10) **Patent No.:** **US D1,081,886 S**
(45) **Date of Patent:** **** Jul. 1, 2025**

(54) **DOMED AND DIMPLED GOLF BALL MARKER**

(71) Applicant: **ON POINT BALL MARKER LLC**, Basalt, CO (US)

(72) Inventors: **Briston Peterson**, Basalt, CO (US); **James Joseph Verna**, Basalt, CO (US)

(73) Assignee: **ON POINT BALL MARKER LLC**, Basalt, CO (US)

(**) Term: **15 Years**

(21) Appl. No.: **29/927,647**

(22) Filed: **Feb. 5, 2024**

Related U.S. Application Data

(63) Continuation of application No. 29/791,612, filed on Jan. 21, 2022, now Pat. No. Des. 1,013,812, which is a continuation of application No. 29/740,638, filed on Jul. 6, 2020, now Pat. No. Des. 956,157, which is a continuation of application No. 29/672,877, filed on Dec. 10, 2018, now Pat. No. Des. 889,580, which is a continuation-in-part of application No. 29/655,568, filed on Jul. 5, 2018, now Pat. No. Des. 872,817.

(57) **CLAIM**

The ornamental design for a domed and dimpled golf ball marker as shown and described.

DESCRIPTION

FIG. 1 is a perspective view of a domed and dimpled golf ball marker in accordance with the new design;

FIG. 2 is a top plan view of FIG. 1;

FIG. 3 is a front elevational view of FIG. 1;

FIG. 4 is a side elevational view of FIG. 1;

FIG. 5 is a bottom exploded perspective view of the domed and dimpled golf ball marker;

FIG. 6 is a bottom plan view of the domed and dimpled golf ball marker;

FIG. 7 is a perspective view of a second embodiment of the domed and dimpled golf ball marker in accordance with a new design;

FIG. 8 is a top plan view of FIG. 7;

FIG. 9 is front elevational view of FIG. 7; and,

FIG. 10 is a side elevational view of FIG. 7.

The broken lines in FIGS. 1-10 illustrate portions of the domed and dimpled golf ball marker that form no part of the claimed design.

1 Claim, 10 Drawing Sheets
